WILLIAM A. READE, OF CLEVELAND, OHIO, ASSIGNOR TO THE LUDLOW TYPOGRAPH COMPANY, OF CLEVELAND, OHIO, A CORPORATION OF MAINE.

TYPOGRAPH MECHANISM.

1,218,803.

Specification of Letters Patent. Patented Mar. 13, 1917.

Application filed May 24, 1911. Serial No. 629,099.

To all whom it may concern:

Be it known that I, WILLIAM A. READE, a citizen of the United States, and a resident of Cleveland, county of Cuyahoga, and State of Ohio, have invented a new and useful Improvement in Typograph Mechanism, of which the following is a specification, the principle of the invention being herein explained and the best mode in which I have 10 contemplated applying that principle, so as to distinguish it from other inventions.

In my co-pending application, filed Feb. 27, 1911, Serial No. 611,246, I have described a form of mold for use in typographs, or 15 similar machines for casting lines of type, whereby such lines of type are formed to accommodate larger type than are found on the matrix bars regularly used. Such larger type, as will be readily understood, are very 20 frequently desired for printing head lines and advertisements, and by this adaptation of the typograph, the necessity for maintaining a stock of "sorts" in order that the printer may be able to set up a form with 25 such larger type, is done away with, since with a single font of matrices of such larger type, any amount of large type matter may be set up. I am aware that it has heretofore been sought to cast slugs with initial 30 letters larger than the body face by simply allowing the matrix of the larger letter, or other character, to overlap the front face of the mold. The slug thus formed will have 35 a thin overlapping body of metal bearing such larger character on its face, which overlapping portion is adapted to extend over the face of an adjacent smooth slug. Although such extended character may be thus supported from below, it is nevertheless so thin that it has a tendency to curl, 40 especially on cylinder presses and when subjected to hard usage.

As in the case of the companion application above identified, the object of the present invention is the avoidance of the difficulty just noted by providing a slug fully as strong and durable as the ordinary one of uniform thickness throughout. To the accomplishment of this and related ends, 50 said invention, then, consists of the means hereinafter fully described and particularly pointed out in the claims.

The annexed drawing and the following description set forth in detail certain mechanism embodying the invention, such dis-

closed means constituting, however, but one of various mechanical forms in which the principle of the invention may be used.

In said annexed drawing:

Figure 1 is a transverse section through a mold and the adjacent parts of a typograph embodying my present improvements; Fig. 2 is a perspective view of an improved matrix bar that forms a feature of the invention; Fig. 3 is a similar view of a blank 65 matrix bar for use in conjunction with the foregoing; Fig. 4 is a perspective view of a slug, or line of type, cast with matrix bars of the kind just referred to; Fig. 5 is a transverse sectional view of an assembled body of 70 such slugs; Fig. 6 illustrates a modification in construction; Fig. 7 is a section of the slugs produced thereby; Fig. 8 is a longitudinal section through the mold illustrating the manner in which a slug such as shown 75 in Fig. 4 may be cast; Fig. 9 is a similar but broken longitudinal sectional view through the mold illustrating the manner in which a different form of slug may be cast; and Fig. 10 illustrates several forms of slugs. 80

As indicated in the above brief description of the drawing, the parts more immediately affected by the present improvement are the mold and matrix bars which coöperate to form the slug or line of type. The 85 form of mold 1 appearing in Fig. 1 is that employed in the so-called Ludlow typograph and is shown in association with the supporting bed 2. The latter may be regarded simply as typical of any suitable support 90 whereon the matrix bars 3 are adapted to rest pending the approach to the mold of the nozzle 4 of the casting pot (not shown), from which molten metal is designed to be supplied to the mold from beneath. The 95 usual terminal "squirt plate" 5 closes the end of the nozzle and directly contacts with the mold, as will be readily understood.

For the casting of slugs of the kind under consideration, the matrix bars 3, or 100 matrices, as they would ordinarily be termed, each have a matrix, that is an intaglio impression, of only a single character, and are correspondingly shorter than the longer bars of the Ludlow typograph 105 whereon a number of matrices are regularly provided. These short matrix bars are furthermore distinguished from short bars heretofore employed in other constructions of typograph, by being more or less deeply 110

recessed on their under faces and having the matrices 6, proper, located at the bottoms of these recesses 7 (see Fig. 2). The recesses in question provide for the formation of a slug 8 with an upper overhanging portion 9 of corresponding dimensions, when a body of such matrices are assembled, as will be readily understood.

The manner in which the matrices are thus assembled and held in place during the casting operation is a matter of indifference; a simple frame 10, preferably of rectangular form, is shown in the drawing, while a presser foot 11 is employed to clamp bars 3 against the casting face of the mold. For forming the spaces between words, as also for leaving blank spaces at the ends of the line where the type matter does not extend through to such ends, I employ bars 12 of the form illustrated in Fig. 3, which differ from the above described matrix bars 3 in that the recesses 13 formed on their under faces are not so deep as recesses 7 and of course do not bear matrices. Such recesses are, however, of a sufficient depth to render continuous the overhanging or enlarged portion 9 of the slug, as will clearly appear from a reference to Fig. 4, in which a slug formed by bars of the kind herein described is shown in perspective. Closure of the respective ends of the space above the upper face of the mold 1 that is laterally inclosed by the walls of the recesses 7 or 13, as the case may be, in the assembled bars, is effected by means of blank bars 14 (see Fig. 8), or equivalent members.

By the mechanism just described I am enabled to cast slugs or lines of type having enlarged upper portions with practically the same facility that ordinary slugs are cast in the regular operation of the typograph. As will be obvious, the slugs formed in this fashion will excel in durability, as well as in the clearness of the impression which they are capable of giving, by reason of the solid support afforded the characters on their faces. It has already been indicated that the casting mechanism may be variously arranged, while still maintaining the advantageous features of the improved matrix bar construction constituting the present invention. There is, in other words, no intention, by referring, as above, to a particular typograph, to imply a limitation in the adaptability of the mechanism; and it should further be borne in mind that such improved bars may be supported directly on the mold face under certain conditions, inasmuch as in the actual casting operation the bars are in effect simply clamped between such face and the under side of the presser foot, or equivalent clamp member.

65 Instead of positioning the assembled body

of matrix bars symmetrically over the slot in the mold, as is illustrated in Fig. 1, such bars, together with their holder, may be shifted to one side or the other as shown in Fig. 6. In this way the form of the slug made from the composite matrix so provided is changed from that of Fig. 5 to that of Fig. 7. The offsetting of the enlarged, type-bearing portions of the slugs thus obtained may be found desirable under certain conditions, and it is entirely feasible to thus form said slugs owing to the relatively large volume of the portion in question, whereas to attempt to do this by similarly overlapping the simple matrix would be entirely impracticable, owing to the chilling of the thin body of metal provided for.

Furthermore, by using bars without any recesses at all, the corresponding section of the slug will, of course, be reduced to simply the relatively narrow body portion. The use of such bars and the formation thereby of slugs thus reduced at one or both ends is occasionally found desirable where a line of large type of greater length than the width of a column is being set up; for in such case it may happen that the space left in a slug for one column will be just a trifle too small to accommodate a letter, as for example a "W," while to shift such letter to the next succeeding slug would leave too large a blank space in the word being composed.

This and similar difficulties may be readily overcome with the improved construction of typograph mechanism under consideration. Thus in the particular case under consideration, the upper, type-bearing portion of the first slug will be extended beyond the body of said slug by allowing the last bar, that carries the matrix of the letter "W" in the assumed instance, to overlap the face of the mold as shown in Fig. 8, thus leaving the end of said slug of the form clearly illustrated at the left in Fig. 10. Due note is, of course, taken of the length of the added or projecting portion of the slug, and in assembling the bars for the next slug, the first bar 15 is a blank one of a width equal to the extra space taken by such end matrix bar in forming the preceding composite matrix, (see Fig. 9); as a result, when the slug is cast, the enlarged portion 9 thereof will terminate short of such end a distance equal to the projection on the preceding slug, as illustrated at the right in Fig. 10. When the two slugs are assembled, accordingly, a continuous effect is secured that would be otherwise impossible.

It will be observed that in all the different forms of slug obtainable by the mechanism herein-before described, while the body of the slug remains of ordinary dimensions in length and width, that is of the same dimen-

sions as it would have were it to bear type characters of regular size, such body is of less than ordinary height by the thickness of the enlarged, or overhanging, portion 9. 5 In this way, the slug may be maintained of standard height, which in the U. S. is 0.918 inch, as is well known. No additional metal is obviously necessary in composing a body of display matter with slugs thus 10 formed, over what would be required in the case of an equal body of ordinary print.

The several novel elements entering into the form and construction of the slugs or type bars, which may be made by my 15 proved typograph mold, as hereinbefore described, have been held to constitute a separate invention from such mold and so are described and claimed in a divisional application filed by me July 3, 1914, Serial No. 20 848,764.

Other modes of applying the principle of my invention may be employed instead of the one explained, change being made as regards the mechanism herein disclosed, 25 provided the means stated by any of the following claims or the equivalent of such stated means be employed.

I therefore particularly point out and distinctly claim as my invention:—

30 1. In mechanism of the character described, the combination with a mold formed with a casting slot; of matrix bars adapted to coöperate therewith, said bars having recesses extending transversely across 35 their faces and of a width greater than that of such slot and type-character impressions being located in such recesses, whereby a slug may be cast with an enlarged upper portion for carrying the line of type; and 40 other bars having blank recesses likewise extending transversely across their faces and of a width greater than that of such slot, such blank recesses being shallower than the recesses bearing the type- 45 character impressions.

2. In mechanism of the character described, the combination with a mold formed with a casting slot; of a composite matrix adapted to coöperate therewith, said 50 matrix being made up partly of bars having recesses extending transversely across their faces and of a width greater than that of such slot, type-character impressions being located in such recesses; and said composite matrix further including bars having blank recesses likewise extending transversely across their faces and of a width greater than that of such slot, such blank recesses being shallower than the recesses bearing the type-character impressions. 55

60 3. In mechanism of the character described, the combination with a mold formed with a casting slot; of a composite matrix adapted to coöperate therewith, said matrix being made up partly of bars having re-

cesses extending transversely across their faces and of a width greater than that of such slot, type-character impressions being located in such recesses; said composite matrix further including bars having blank 70 recesses likewise extending transversely across their faces and of a width greater than that of such slot, such blank recesses being shallower than the recesses bearing the type-character impressions; and another 75 blank bar at the end of such slot and entirely closing the same.

4. In mechanism of the character described, the combination with a mold formed with a casting slot; of a matrix adapted to 80 coöperate therewith, said matrix having a recess extending transversely across its face, type-character impressions being located in such recess and the latter being wider than such slot and also longer, whereby a slug 85 may be cast having a type-face projecting beyond the end of the slug body, substantially as described.

5. In mechanism of the character described, the combination with a mold formed 90 with a casting slot; of a composite matrix adapted to coöperate therewith, said matrix being made up partly of bars having recesses extending transversely across their faces and of a width greater than that of such slot, 95 type-character impressions being located in such recesses, a terminal one of said bars extending beyond the end of such slot.

6. In mechanism of the character described, the combination with a mold formed 100 with a casting slot; of a composite matrix adapted to coöperate therewith, said matrix being made up partly of bars having recesses extending transversely across their faces and of a width greater than that of such slot, 105 type-character impressions being located in such recesses, a terminal one of said bars extending beyond the end of such slot; and said composite matrix further including bars having blank recesses likewise 110 extending transversely across their faces and of a width greater than that of such slot, such blank recesses being shallower than the recesses bearing the type-character impressions. 115

7. In mechanism of the character described, the combination with a mold formed with a casting slot; of a pair of matrices respectively adapted to coöperate therewith, one such matrix being longer than such casting slot, whereby a slug may be cast having a type-face projecting beyond the end of the slug-body, and the other such matrix being shorter than such casting slot by an amount substantially equal to the projection of such first matrix, whereby a slug may be cast having a type-face correspondingly shorter than such first-named slug and the one may terminally overlap the other to present an unbroken line of type characters. 120 125 130

8. In mechanism of the character described, the combination with a mold formed with a casting slot; of a pair of composite matrices respectively adapted to coöperate therewith, one such matrix being longer than such casting slot, whereby a slug may be cast having a type-face projecting beyond the end of the slug-body, and the other such matrix being shorter than such casting slot by an amount substantially equal to the projection of such first matrix, whereby a slug may be cast having a type-face correspondingly shorter than such first-named slug and the one may terminally overlap the other to present an unbroken line of type characters.
9. In mechanism of the character described, the combination with a mold formed with a casting slot; of a pair of composite matrices respectively adapted to coöperate therewith, each such matrix being made up partly of bars having recesses extending transversely across their faces and of a width greater than that of such slot, the type-character impressions being located in such recesses, a terminal one of said recessed bars in the base of one matrix extending beyond the end of such slot and the other matrix including a blank bar closing one end of such slot an amount substantially equal to the amount such recessed bar in said first matrix extends beyond such slot, whereby terminally overlapping slugs may be cast presenting an unbroken line of type characters.
10. In mechanism of the character described; the combination with a mold formed with a casting slot of ordinary length and width but of a height less than standard; of matrix bars adapted to coöperate therewith, said bars having recesses extending transversely across their faces and of a width greater than that of such slot and type character impressions being located in such recesses, whereby a slug may be cast with an enlarged upper portion for carrying the line of type; and other bars having blank recesses likewise extending transversely across their faces and of a width greater than that of such slot, such blank recesses being shallower than the recesses bearing the type-character impressions.
11. In mechanism of the character described, the combination with a mold formed with a casting slot of length and width the same as, but of height less than, standard; of a composite matrix adapted to coöperate therewith, said matrix being made up partly of bars having recesses extending transversely across their faces and of a width greater than that of such slot, type-character impressions being located in such recesses; and said composite matrix further including bars having blank recesses likewise extending transversely across their faces and of a width greater than that of such slot, such blank recesses being shallower than the recesses bearing the type-character impressions.
12. In mechanism of the character described, the combination with a mold formed with a casting slot of length and width the same as, but of height less than, standard; of a composite matrix adapted to coöperate therewith, said matrix being made up partly of bars having recesses extending transversely across their faces and of a width greater than that of such slot, type-character impressions being located in such recesses; said composite matrix further including bars having blank recesses likewise extending transversely across their faces and of a width greater than that of such slot, such blank recesses being shallower than the recesses bearing the type-character impressions; and another blank bar at the end of such slot and entirely closing the same.
13. In mechanism of the character described, the combination with a mold formed with a casting slot of length and width the same as, but of height less than, standard; of a composite matrix adapted to coöperate therewith, said matrix being made up partly of bars having recesses extending transversely across their faces and of a width greater than that of such slot, type-character impressions being located in such recesses, a terminal one of said bars extending beyond the end of such slot.
14. In mechanism of the character described, the combination with a mold formed with a casting slot of length and width the same as, but of height less than, standard; of a composite matrix adapted to coöperate therewith, said matrix being made up partly of bars having recesses extending transversely across their faces and of a width greater than that of such slot, type-character impressions being located in such recesses, a terminal one of said bars extending beyond the end of such slot; and said composite matrix further including bars having blank recesses likewise extending transversely across their faces and of a width greater than that of such slot, such blank recesses being shallower than the recesses bearing the type-character impressions.

Signed by me this 16th day of May, 1911.
WILLIAM A. READE.
